UNITED STATES PATENT OFFICE.

FREDERICK J. HUMPHREY, OF KALAMAZOO, MICHIGAN.

WATER-MOTOR.

SPECIFICATION forming part of Letters Patent No. 738,806, dated September 15, 1903.

Application filed July 5, 1902. Serial No. 114,412. (No model.)

To all whom it may concern:

Be it known that I, FREDERICK J. HUMPHREY, a citizen of the United States, residing at the city of Kalamazoo, in the county of Kalamazoo and State of Michigan, have invented certain new and useful Improvements in Water-Motors, of which the following is a specification.

This invention relates to improvements in water-motors, and particularly to motors adapted for pumping purposes.

The objects of the invention are, first, to provide an improved water-motor which is positive in its valve action and one which is simple in its structure and operation and which will perform a maximum of work for the power consumed; second, to simplify the construction and arrangement of the parts in a water-motor to produce a structure which is economical to manufacture and also one which is durable and not liable to get out of repair, but one which, should this occur, may be quickly and easily repaired, because all the working parts are simple and such as are in common use; third, to provide an improved valve mechanism for water-motors or similar engines; fourth, to provide an improved construction of water-motor or similar engine in which the shock in reversing the engine shall be of no consequence.

Further objects will definitely appear in the detailed description to follow.

I accomplish the objects of my invention by the devices and means described in the following specification.

The invention is clearly defined, and pointed out in the claims.

A structure embodying the features of my invention is fully illustrated in the accompanying drawings, forming a part of this specification, in which—

Figure 1 is a detail longitudinal sectional view of a structure embodying the features of my invention, taken on line 1 1 of Figs. 2 and 3. Fig. 2 is a detail cross-sectional view taken on line 2 2 of Fig. 1. Fig. 3 is a detail cross-sectional view taken on line 3 3 of Fig. 1. Fig. 4 is a detail longitudinal sectional view taken on a line corresponding to the irregular line 4 4 of Fig. 2. Fig. 5 is a detail longitudinal sectional view taken on line 5 5 of Fig. 2. Fig. 6 is a diagrammatical

view showing the circulation and the relative position of the parts in operation.

In the drawings all of the sectional views 55 are taken looking in the direction of the little arrows at the ends of the section-lines.

Similar letters of reference refer to similar parts throughout the several views.

Referring to the lettered parts of the drawings, A is the motor-cylinder, A' the pump-cylinder, and A'' a supporting-bracket connecting and supporting the cylinders and their attached parts.

In the motor-cylinder A is a piston B, which 65 is connected to the pump by a piston-rod B'. The main-valve chamber C, which is cylindrical, is arranged to one side of the pump-cylinder A, the central portion of the same being of a slightly-reduced bore, as at C''. In 70 the main-valve chamber are reciprocating piston-valves C' C', oppositely arranged, each having three heads o, fitting the small bore at the center, and p and q in the enlarged ends, all provided with hydraulic packings, that of 75 the head q pointing in both directions. Chambers are formed between the several heads.

Arranged to one side of the valve-chamber C is an auxiliary or trip valve chamber D, with a valve D' therein, having heads d d to- 80 ward each end with hydraulic packings.

The valves C' C' control the movement of the piston B in the motor-cylinder by connecting the same alternately to the induction and exhaust passages. The valves C' C' are 85 controlled by the auxiliary valve D'. The auxiliary or trip valve D' is controlled by the movement of the motor-piston B in the cylinder A, which acts as a valve therefor.

I will now describe the parts and the connecting passages and ports in detail.

An inlet or induction passage G is provided, which terminates in an annular passage b, centrally located about the main-valve chamber and which communicates therewith by 95 ports b'. Ports a'' to either side of the ports b' communicate with the annular passages a', located to each side of the annular passage b, and these passages are connected to the main passages a, leading to the ends of the motor-cylinder and opening into the same at points beyond the stroke of the piston B for the purpose of controlling the same. The ports a'' are located far enough from the ports b' to be

cut off therefrom by the packings of the head *o* when the valve *C'* at that end is in its inner position and connected therewith when such valve *C'* is in its outer position. (See Figs. 5 1 and 6.) Exhaust or eduction passages *E' E'*, which unite in the main exhaust-passage *E*, are formed in the enlarged part of the main-valve chamber at each side of the center. These eduction-passages *E'* are located far 10 enough from the ports *a''* to be cut off therefrom when a valve *C'* is in its outer position and so as to be connected therewith when the valve is in its inner position. (See Figs. 1 and 6.) It is thus clear that the passages *a* 15 serve the usual function of such passages in engine-cylinders. Centrally located about the chamber of the auxiliary or trip valve *D'* is an annular passage *j*. The passage *j* is connected to the trip-valve chamber by suitable ports and to the induction-passage *b* by a passage *j'*. A passage *e* at each side connects the annular port *i* to the outer end of chamber of valve *C'* to carry water to and from the same in its operation, which flow is 25 controlled by the auxiliary valve *D'*. Annular passages *i i* are around each end of the chamber of the auxiliary valve *D'*, so that the valve *D'* connects the same alternately with the central passage *j* like a **D**-valve of an engine. 30 There are passages *n* in each end of the valve-chamber, to which the passages *i* are connected for exhaust. This is the same as for an engine-valve, except each end of the valve connects and exhausts for an independent 35 piston—that is, for piston-valves *C' C'*. The passages *n* also serve as passages to and from the pistons of valve *D'* to actuate the same, as will be hereinafter explained. A passage *n* connects each end of the auxiliary- 40 valve chamber beyond the stroke of the valve *D'* with the corresponding main-valve chamber at a point in the same far enough removed from the exhaust-port *E'*, so that the packing of head *p* will disconnect the same 45 therefrom when the valve *C'* is in the inner position and near enough thereto to be connected with the exhaust-ports *E'* by being embraced with said port *E'* between the heads *o* and *p* of the valves *C'* when the valve is 50 shifted to the outer position. The passage *n* at each side can therefore be connected alternately with pressure and exhaust to actuate the auxiliary valve *D'*, and that is one of their purposes. Small passages *c* connect 55 from toward each end the motor-cylinder with the corresponding main-valve chamber *C*, the passages opening into the motor-cylinder at points just within the stroke of the piston-head and into the main-valve chamber at 60 points which are always between the packings of heads *p* and *q* of the valves *C'*, no matter what the position of the valves. These passages *c* therefore connect the main cylinder with the auxiliary valve *D'* at each end of 65 the piston-stroke by connecting the pressure to the passages *n* alternately through the valves *C'* and insures the actuation of the

valve *D'*. The engine-cylinder acts as the engine-valve to the piston of auxiliary valve *D'*.

The general arrangement of the ports and 70 passages having been described, the operations of the structure will be pointed out.

With the piston and valves in the initial positions shown in the drawings the water is admitted through the inlet or induction pipe *G*, passes into the main-valve chamber through the ports *b*, and out through the ports *a''*, to the right in Figs. 1 and 6, leading to the end of the motor-cylinder. When the piston *B* passes the passage *c* at the opposite 80 end of the motor-cylinder, water is admitted through the same into the main-valve chamber and through the passage *n* to the corresponding end of the auxiliary-valve chamber. This, as the opposite end of the auxiliary chamber is then connected through the opposite passage *n* to an exhaust-port *E'*, (see the right of Figs. 1 and 6,) forces the valve *D'* to the opposite end of the auxiliary-valve chamber, which connects the passage *e* at 85 that end to the passage *j*, the water passing into the auxiliary-valve chamber through the annular port *j* and out of the same through the annular port *i* at the right of Figs. 4 and 6, the valves *D'* being then in position to connect these ports. The direct pressure of the water against the outer end of the opposite valve *C'* forces the same inward, cuts off the supply of water, and connects that end of the motor-cylinder to the exhaust. The opposite 90 end of the main-valve chamber is thus connected through the passages *e*, *n*, and *c* and the intervening portions of the chambers *D* and *C* to the motor-cylinder behind the piston, which by this time is in communication 95 at the opposite end of the exhaust, thus allowing the other valve *C'* to shift outwardly. The position of the valves is then the reverse of that shown in the drawings. This connects the opposite end of the motor-cylinder 100 to the exhaust-passage *E'* at that end and connects the water to the other end, whereby the action is reversed and the direction of the water through the several passages will be 105 the reverse of that described. By this arrangement of valves and passages a gradual 110 action of the valves is secured, so that although their action is prompt it is practically without shock or pounding.

It will be seen that as the valves are operated by the full water-pressure a prompt and sure action of the same is insured. It will further be noted that as soon as the position of the valves is shifted the motor-cylinder is free to exhaust through the passage *a* at that 115 end of the motor-cylinder which is then connected to the exhaust, which insures a very prompt action of the motor.

I have illustrated and described my improved water-motor in detail in the form preferred by me on account of its simplicity of construction. I am aware, however, that it is capable of numerous modifications and changes in structural details without depart- 120 125 130 135

ing from my invention. As such changes will readily appear to those skilled in the art to which my invention appertains, they are not here described.

5 Having thus described my invention, what I claim as new, and desire to secure by Letters Patent, is—

1. In a water-motor, the combination of a motor-cylinder A; a piston-head B therefor; 10 a main-valve chamber C, the central portion of which is of lesser diameter, as at C''; valves C' C' having heads o, p and q with suitable packings oppositely arranged in said main-valve chamber; an auxiliary or trip valve chamber D; a valve D' therefor having packings d d; an annular induction-passage b centrally located about said main-valve chamber and connected thereto by suitable ports, as b'; annular passages a' located to 15 each side of the annular passage b and connected to the main-valve chamber by suitable ports as a''; passages a a connected to said annular passages a' and opening into the motor-cylinder at each end at points beyond the stroke of the piston-head; an annular passage j centrally located about said auxiliary-valve chamber and connected therewith by suitable ports; annular passages i i about 20 said auxiliary-valve chamber, located to each side of the said annular passage j; a passage j' connecting the said passages j and b; a passage c at each end connecting said main-valve chamber at points between the corresponding valve-heads p q and the main motor-cylinder at each end at points within the stroke of the piston-head; passages n n connecting the outer ends of the trip or auxiliary valve chamber D to the main-valve chamber; 25 passages e connecting the ends of the main-valve chamber to the passages i; and exhaust-ports E' in said main-valve chamber, said passages being so arranged as to be alternately connected with the induction and exhaust ports as the said valves are automatically shifted, all coacting substantially as described and for the purpose specified.
2. In a water-motor, the combination of a motor-cylinder A; a piston-head B therefor; a main-valve chamber C, the central portion of which is of lesser diameter, as at C''; valves C' C' having heads o, p, q, with suitable packings, oppositely arranged in said main-valve chamber; an auxiliary or trip valve chamber D; a valve D' therefor having hydraulic packings d d; an induction-passage for said main-valve chamber; passages a a connected to said main-valve chamber at each side of the said induction-passage and opening into the motor-cylinder at each end at points beyond the stroke of the piston-head; a passage connecting said auxiliary-valve chamber with the said induction-passage; passages c connecting said main-valve chamber at points between the valve-heads p and q and the corresponding ends of the motor-cylinder, within the stroke of the piston-head respectively; 30 passages n n connecting the outer ends of the trip or auxiliary valve chamber to the main-valve chamber; passages e connecting the ends of the main-valve chamber to the auxiliary-valve chamber at points to each side of the induction-passage; exhaust-ports E' in the said main-valve chamber and suitable valves adapted to alternately connect the ends of the trip or auxiliary valve chamber to the main-valve chamber; passages e connecting the ends of the main-valve chamber 35 to the auxiliary-valve chamber at points to each side of the induction-passage thereof; and exhaust-ports E' in said main-valve chamber, said passages being arranged so as to be alternately connected with the induction and exhaust ports as the said valves are automatically shifted, all coacting substantially as described and for the purpose specified.
3. In a water-motor, the combination of a motor-cylinder A; a piston-head B therefor; a main-valve chamber C, the central portion of which is of lesser diameter, as at C''; an annular induction-passage centrally located about said main-valve chamber and connected thereto by suitable ports; annular passages a' located to each side of the annular passage b, and connected to the main-valve chamber by suitable ports, as a''; 40 passages a a connected to said annular passages a' and opening into the motor-cylinder at points beyond the stroke of the piston-head; an auxiliary-valve chamber; an annular passage j centrally located about said auxiliary-valve chamber and connected therewith by suitable ports; annular passages i i about 45 said auxiliary-valve chamber, located to each side of the said annular passage j; a passage j' connecting said main-valve chamber and auxiliary-valve chamber; passages c connecting the main-valve chamber at points between the valve-heads p and q to the corresponding ends of the motor-cylinder within the stroke of the piston-head, respectively; passages n n connecting the outer ends of the trip or auxiliary valve chamber to the main-valve chamber; 50 passages e connecting the ends of the main-valve chamber to the passages i; and exhaust-ports E' in said main-valve chamber; suitable valves in said valve-chambers whereby said passages are alternately connected to the induction and exhaust ports as the valves are shifted, substantially as described.
4. In a water-motor, the combination of a motor-cylinder A; a piston-head B therefor; a main-valve chamber C, the central portion of which is of lesser diameter, as at C''; an induction-passage for said main-valve chamber; 55 passages a a connected to said main-valve chamber at each side of the said induction-passage, and opening into the motor-cylinder at points beyond the stroke of the piston-head; an auxiliary-valve chamber; a passage connecting said auxiliary-valve chamber with the said induction-passage; passages c connecting said main-valve chamber and motor-cylinder; 60 passages n n connecting the outer ends of the trip or auxiliary valve chamber to the main-valve chamber; passages e connecting the ends of the main-valve chamber to the auxiliary-valve chamber at points to each side of the induction-passage; exhaust-ports E' in the said main-valve chamber and suitable valves adapted to alternately connect the ends of the trip or auxiliary valve chamber to the main-valve chamber; 65 passages e connecting the ends of the main-valve chamber to the auxiliary-valve chamber at points to each side of the induction-passage thereof; and exhaust-ports E' in said main-valve chamber, said passages being arranged so as to be alternately connected with the induction and exhaust ports as the said valves are automatically shifted, all coacting substantially as described and for the purpose specified.

nect said passages to the induction and exhaust ports, whereby said valves are automatically shifted, as specified.

5. In a water-motor, the combination of a motor-cylinder A; a piston-head B therefor; a main-valve chamber C, the central portion of which is of a lesser diameter, as at C"; an induction-passage for said main-valve chamber; passages *a a* connected to said main-valve chamber at each side of the said induction-passage, and opening into the motor-cylinder at points beyond the stroke of the piston-head; an auxiliary-valve chamber, a passage connecting said auxiliary-valve chamber with the said induction-passage; connecting-passages for the outer ends of the auxiliary-valve chamber to the motor-cylinder, said passages opening into the motor-cylinder at points within the stroke of the piston-head; passages *e* connecting the ends of the main-valve chamber to the auxiliary-valve chamber at points to each side of the induction-passage; exhaust-ports *E'* in said main-valve chamber; and suitable valves in said valve-chambers adapted to alternately connect said passages to the induction and exhaust ports, whereby said valves are automatically shifted, as specified.

6. In a water-motor, the combination of a motor-cylinder; a suitable piston-head therefor; a main-valve chamber, the central portion of which is of slightly-reduced bore; an auxiliary-valve chamber; an induction-passage opening into said main-valve chamber at a central point; passages opening into said main-valve chamber to each side of said induction-passage, and into said motor-cylinder at a point beyond the stroke of the piston-head; an induction-passage opening into said auxiliary-valve chamber at a central point therein; passages opening into the main-valve chamber toward its end, and into the auxiliary-valve chamber to each side of its induction-port; passages *c* connecting the main-valve chamber with the motor-cylinder, said passages opening into the motor-cylinder at points within the stroke of the piston-head; passages connecting the outer ends of the auxiliary-valve chamber to the main-valve chamber; exhaust-ports opening into said main-valve chamber, and suitable valves for said main and auxiliary valve chambers, adapted to alternately connect said passages to the induction and exhaust ports, substantially as described.

7. In a water-motor, the combination of a motor-cylinder; a suitable piston-head therefor; a main-valve chamber, the central portion of which is of slightly-reduced bore; an auxiliary-valve chamber; an induction-passage opening into said main-valve chamber at a central point; passages opening into said main-valve chamber to each side of said induction-passage, and into said motor-cylinder at a point beyond the stroke of the piston-head; an induction-passage opening into said

auxiliary-valve chamber at a central point therein; passages opening into the main-valve chamber toward its end, and into the auxiliary-valve chamber to each side of its induction-port; connecting-passages for the outer ends of the auxiliary-valve chamber to the motor-cylinder, said passages opening into the motor-cylinder at points within the stroke of the piston-head; exhaust-ports opening into said main-valve chamber, and suitable valves for said main and auxiliary valve chambers, adapted to alternately connect said passages to the induction and exhaust ports, substantially as described. 8c

8. In a water-motor, the combination of a motor-cylinder; a single-headed piston therefor; a main piston-valve; an auxiliary piston-valve; an induction-passage for the main-valve chamber; passages connecting said main-valve chamber to said motor-cylinder, said passages opening into said motor-cylinder at points beyond the stroke of the piston-head; an induction-passage for said auxiliary-valve chamber; passages connecting the ends of the main-valve chamber to the auxiliary-valve chamber; connecting-passages for the ends of the auxiliary-valve chamber to the motor-cylinder, said passages opening into the motor-cylinder at points within the stroke of the piston-head; exhaust-ports in said main-valve chamber, and suitable heads for the valves, adapted to alternately connect the said passages to the induction and exhaust ports, whereby the valves are automatically shifted, for the purpose specified.

9. In a water-motor, the combination of an engine-cylinder; with piston therein; a main piston-valve therefor in two independently-movable symmetrical halves toward each end of the engine, adapted to be actuated by the water-pressure; an auxiliary piston-valve, also adapted to be actuated by water-pressure; passages from the main valve to the engine-cylinder; passages from the auxiliary valve to the main-valve chamber to actuate the pistons of the main valve; passages from the engine-cylinder toward each end within the stroke of the piston, connecting to the piston-cylinder chambers of the main valve between the heads of its pistons; suitable exhaust-ports in said main-valve chamber and passages from the said cylinder-chambers of the main valve to the pistons of the auxiliary valve, positioned to be connected alternately with space between the valve piston-heads and the exhaust, whereby the auxiliary valve will be actuated from the motor-cylinder pressure, coacting as specified. 125

In witness whereof I have hereunto set my hand and seal in the presence of two witnesses.
